US00D896217S

(12) **United States Design Patent** (10) Patent No.: **US D896,217 S**
(45) Date of Patent: ** Sep. 15, 2020

(54) **HOUSING OF AN ELECTRONIC DEVICE**

(71) Applicant: **Advanced Micro Devices, Inc.**, Santa Clara, CA (US)

(72) Inventors: **Christopher Jagers**, Austin, TX (US); **David McAfee**, Austin, TX (US); **Matthew C. Grossman**, Austin, TX (US); **Christopher Cavello**, Austin, TX (US); **Christopher Janak**, Austin, TX (US); **Steve Capezza**, Austin, TX (US); **Carlos Santillana**, Cedar Park, TX (US)

(73) Assignee: **Advanced Micro Devices, Inc.**, Santa Clara, CA (US)

(**) Term: **15 Years**

(21) Appl. No.: **29/723,393**

(22) Filed: **Feb. 6, 2020**

Related U.S. Application Data

(62) Division of application No. 29/615,083, filed on Aug. 25, 2017, now Pat. No. Des. 878,359, which is a division of application No. 29/548,331, filed on Dec. 11, 2015, now Pat. No. Des. 798,904.

CLAIM

The ornamental design for a housing of an electronic device, as shown and described.

DESCRIPTION

FIG. 1 is a top perspective view of a housing of an electronic device;

FIG. 2 is a bottom perspective view of a housing of an electronic device;

FIG. 3 is a front view of a housing of an electronic device;

FIG. 4 is a rear view of a housing of an electronic device;

FIG. 5 is a first side view of a housing of an electronic device;

FIG. 6 is a second side view of a housing of an electronic device;

FIG. 7 is a top plan view of a housing of an electronic device; and,

(Continued)

FIG. 8 is a bottom plan view of a housing of an electronic device.

1 Claim, 6 Drawing Sheets
